his Atty.

UNITED STATES PATENT OFFICE.

HARRY HIRSCHL, OF WASHINGTON, MISSOURI.

TOBACCO-SMOKING PIPE.

Application filed April 14, 1925. Serial No. 23,019.

This invention relates to an improvement in tobacco smoking pipes, and is especially designed with the view of providing a wooden stem of special construction, which is secured to a particular type of mouth piece used in connection with a corn cob bowl, thereby producing a pipe possessing a pleasing, attractive, novel, and ornamental appearance.

10 The main object of the invention is to provide a simple, economical and durable smoking pipe, stem and mouth piece possessing novel characteristics, which when assembled together constitutes a novel, attractive and pleasing product.

Another object of this invention is to provide a novel and ornamental wooden stem which is formed from a single piece and so fitted to a corn cob bowl as to cover the inner pithy bottom portion of the bowl, thus forming a more solid and durable bottom therefor, which stem is formed circular at its inner end which is fitted to the pipe bowl, while its outer end terminates with flattened sides terminating in alinement with the flat sides of the mouth piece, the latter being suitably fitted to the said wooden stem.

30 A further object of this invention is to combine a specially constructed stem and mouth piece with a corn cob pipe bowl specially prepared under the process granted to me by Letters Patent dated October 31, 1922, No. 1,434,119, thereby producing a product of a more graceful and pleasing appearance.

The foregoing and such other objects as may appear from the ensuing description are attained by the construction, arrangement, location and combination of the several parts hereinafter more fully described, illustrated by the accompanying drawings, and more particularly set forth in the claims appended hereto, it being understood that slight changes in the precise proportions and minor details of construction may be resorted to without departing from the spirit or sacrificing any of the advantages of the invention.

50 In the accompanying drawings forming a part of this specification it will be seen that:

Figure 1 is a side elevation of the improved smoking pipe embodying my invention.

55 Fig. 2 is a plan view of the same.

Fig. 3 is a central section taken through

the wooden stem and corn cob bowl with the mouth piece removed.

Fig. 4 is a side elevation of the wooden mouth piece in its original formation, and before it has been ornamented and fitted to the pipe bowl, and

Fig. 5 is a side elevation of a slightly modified form of pipe and stem.

In the embodiment of my invention as illustrated the numeral 1 designates a specially prepared corn cob bowl provided with a circular opening through its walls near the bottom thereof leading to the interior of the bowl for the reception of a wooden stem 2, formed from a single piece of suitable wood, having a circular or round inner end portion 3 which is fitted into the said opening in the pipe bowl, the extreme inner end portion of said stem being so cut and formed as to provide a solid wood concaved bottom 4 for the inner portion of the bowl with a portion 5 of the stem extended upwardly in alinement with the inner wall of the bowl, thus covering and protecting the pithy bottom of the bowl and lower portion of the inner and lower side walls thereof and serving to prevent rapid burning out of the bowl and the points where it is most liable to burn out quickly on account of the hard material forming the bottom of the bowl and stem, said stem having a gradually enlarged opening formed through its longitudinal center leading from the inner wall of the bowl to the outer end of the stem.

It will be seen that each of the four sides of the wooden stem is flattened gradually inwardly from its outer end portion 6, toward its inner end portion, each flattened portion merging into a round or circular portion at or near that point where the stem enters into the body of the corn cob bowl, and that each of the flattened sides is ornamented to represent a corn cob stem, or the said flattened sides may be otherwise suitably enameled or desirably ornamented, each outer corner of the flattened portion terminating in alinement with a specially constructed mouth piece 7, preferably formed of suitable transparent material having flattened sides, the inner edges of which terminate in alinement with the other side edges of the stem, each inner edge of the stem member being gradually tapered or inclined outwardly to the point 8, as clearly shown in Fig. 1, and at the inner end of the said mouth piece is formed a suitable screw-

2
threaded connection by which the mouth piece is removably secured to the threaded portion 9 of the wooden pipe stem.

At the juncture between the mouth piece 5 and pipe stem is preferably secured in any suitable or desirable manner a band of metal 10, formed of any desired material preferably of an ornamental nature which serves to furnish a more finished appearance to the 10 product, although this metal band may be dispensed with if desired.

In the modified construction of pipe and stem shown in Fig. 5, it will be seen that the bowl 11 is formed entirely of corn cob varnished on its outer surface in the usual manner and connected to said bowl is a wooden stem 12 having a small opening formed through its inner end portion leading into an enlarged opening extending to the outer 20 end of the stem, as shown by dotted lines, said enlarged opening terminating with a smooth interior surface, adapted for the reception of the inner end of a mouth piece 13 of the push or slip stem type. The wooden 25 stem 12 is suitably ornamented on its outer surface and formed with a square outer end portion, around which end portion is preferably placed a metallic sleeve 14, each corner of the squared portion being beveled 30 gradually inwardly and merging into a round or circular portion at its entrance in-

to the outer surface of the pipe bowl as will be readily understood.

It will be readily perceived that by the use 35 of my specially prepared corn cob pipe bowl, in connection with the specially constructed ornamental wooden stem, and the precise form of mouth piece employed with the stem, that a more durable corn cob pipe bowl is the result, and that an improved smoking 40 pipe possessing an ornamental, pleasing and attractive appearance is the resulting product when assembled together in the manner hereinbefore referred to.

It will also be understood that the wooden 45 stem may be so shaped as to fit a mouth piece having any number of flat outer surfaces.

Having thus described my invention what I claim and desire to secure by Letters Patent is:—

A tobacco smoking pipe of the character described, comprising a corn cob bowl having a round opening in one side near the bottom thereof, a wooden stem formed of a single piece having a round inner end portion fitted in said opening and flattened side portions terminating with a square outer end, with the extreme inner end portion of said stem forming a solid concaved bottom 55 for the inner portion of the bowl and forming a portion of the inner wall of said bowl. 60

HARRY HIRSCHL.
